UNITED STATES PATENT OFFICE.

OLOF JANSSON, OF WEST SWEDEN, WISCONSIN.

POCKET-INKSTAND.

SPECIFICATION forming part of Letters Patent No. 286,703, dated October 16, 1883.

Application filed May 10, 1883. (No model.)

To all whom it may concern:

Be it known that I, OLOF JANSSON, a citizen of the United States, residing at West Sweden, in the county of Polk and State of Wisconsin, have invented certain new and useful Improvements in Pocket-Inkstands; and I do hereby declare that the following is a full, clear, and exact description of the same, reference being had to the annexed drawings, making a part of this specification, and to the letters and figures of reference marked thereon.

Figure 1 of the drawings is a longitudinal section of a pocket-inkstand constructed in accordance with my invention and on an enlarged scale; Fig. 2, a detail view of the circular plate for holding the ink-receptacle in the case; Fig. 3, a similar view of the hinged plate for closing the mouth of the ink-receptacle; Fig. 4, a detail view of the slotted plate to which the hinged plate shown in Fig. 3 is connected, and Fig. 5 a similar view of the spring-catch.

The present invention has relation to certain new and useful improvements in that class of pocket-inkstands in which the glass ink-receptacle is of hemispherical form held within a case provided with a screw-threaded cover, the mouth of the receptacle being closed by a packing connected to a removable plate held in position by a spring-catch.

The invention consists, in connection with the above construction, of providing a slotted plate or disk for holding the ink-receptacle in position within the case, substantially as shown in the drawings, and hereinafter described and claimed. These several objects I attain by the construction substantially as shown in the drawings, and hereinafter described and claimed.

In the accompanying drawings, A represents the case for containing the ink-receptacle, which may be of wood, rubber, or other suitable material, and of circular form. The case A has an externally-screw-threaded flange, *a*, and an annular shoulder *b* to receive the internally-screw-threaded cover B, and when in place, as shown in Fig. 1, the inkstand is perfectly smooth upon its top, sides, and bottom, and, in addition, it is very low and wide, thus making it compact and easily carried in the pocket, and its wide base renders it less

liable to tip over when on the writer's desk or table. The case A is formed with a hemispherical seat, *c*, for the ink-receptacle C, said receptacle being of glass and of hemispherical form, as shown, and has a suitable neck, *d*. This peculiar form of ink-receptacle renders it less liable to burst from the freezing of the ink, as when the receptacle is filled with ink only to that extent or so far as to leave a small space between the ink and neck of the receptacle and in such condition standing on the table or desk, the bottom and sides thereof being slanting or on an incline, the frozen ink, when expanding, has no flat surface to press against, and consequently will move gently in an upward direction to fill the unoccupied space. Thus comparatively little lateral pressure is brought against the glass. The receptacle C is held down upon the hemispherical seat *c* by a disk or metal plate, D, secured to the flange *a* by screws *e* or other like fastenings, said disk D having a circular opening, *f*, through which projects the neck *d*. The mouth of the neck *d* is closed by a packing, *g*, of rubber, cork, or other like material used for the purpose, said packing being suitably connected to a plate, E, having downwardly-curved extensions *h i*. This plate E is hinged to a slotted plate, *k*, which is securely fastened at its lower end to the case A, its upper or slotted end extending up through an elongated slot, *l*, in the disk D. The extension *h* of the plate E is passed through the slotted end of the plate *k*, and afterward bent around the same, thus making a hinged connection between the plates *k* and E. The disk D has a slot, *m*, diametrically opposite the slot *l*, through which passes the upper end of a spring-catch, F, secured at its lower end to the case A. This catch F, when the plate E is in position over the mouth *d*, extends over the end of the extension *i*, and thus firmly holds the packing *g* down upon the neck of the ink-receptacle, and by pressing the catch outward it will be disengaged from the extension of the plate and allow the same to be removed.

The above-described means for securing the ink-receptacle in the case and closing the mouth of the same are both simple and practical, and the mouth is closed so effectually and with comparatively little trouble that it is impos-

sible for the ink to escape while the inkstand is being carried in the pocket. The peculiar form also of the case and cover renders it more convenient to carry on the person than those pocket-inkstands having a high neck, while the inkstand constructed in accordance with my invention not only possesses the many advantages above enumerated, but may be manufactured and placed in the market at a very small cost, thus bringing it within the reach of those requiring such an article.

Having now fully described my invention, what I claim as new, and desire to secure by

15 Letters Patent, is—

1. The case A, having hemispherical seat c and cover B, in combination with the hemi-

spherical-shaped glass ink-receptacle C, confining-disk D, and hinged plate E, carrying packing g, substantially as and for the purpose set forth.

2. The case A, having cover B, and slotted plate or disk D, and the spring-catch F, in combination with the ink-receptacle C, and hinged plate E, having downwardly-curved extensions h i, and packing g, substantially as and for the purpose specified.

In testimony that I claim the above I have hereunto subscribed my name in the presence of two witnesses.

OLOF JANSSON.
